(57) **CLAIM**

The ornamental design for universal tilt and swivel stand as shown and described.

DESCRIPTION

FIG. 1 is a front isometric view of a universal tilt and swivel stand according to the invention;

FIG. 2 is a rear isometric view thereof;

FIG. 3 is a right elevation view thereof;

FIG. 4 is a left elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines shown in the drawings represent portions of the universal tilt and swivel stand that form no part of the claimed design.

1 Claim, 8 Drawing Sheets
